JOSEPH ROBLEY, OF BROOKLYN, NEW YORK, ASSIGNOR TO WILLIAM M. BRASHER & CO., OF SAME PLACE.

Design No. 4,712, dated March 14, 1871.

DESIGN FOR A FLOOR OIL-CLOTH PATTERN.

The Schedule referred to in these Letters Patent and making part of the same.

To all whom it may concern:

Be it known that I, JOSEPH ROBLEY, of the city of Brooklyn, L. I., county of Kings and State of New York, have invented or produced a new and original Design for a Pattern to be printed upon Floor Oil-Cloths in colors similar to those painted on the drawings accompanying this specification, or in other colors substituted in the place of those printed on the drawings herewith; and I do hereby declare that the drawings accompanying this specification do give and convey to any one skilled in the art of manufacturing floor oil-cloth a thorough description of the nature of my invention, and are sufficient to enable any one skilled in the art of manufacturing floor oil-cloth to use my invention.

What I claim as my invention, and desire to secure by Letters Patent, is—

The configuration of the design hereunto annexed, when made by being wrought upon floor oil-cloth in the form similar to the drawings accompanying this specification.

JOSEPH ROBLEY.
